UNITED STATES PATENT OFFICE

119,005

DESIGN FOR A TEXTILE FABRIC

Louis G. Meurer, New York, N. Y.

Application November 18, 1939, Serial No. 88,358

Term of patent 3½ years

To all whom it may concern:

Be it known that I, Louis G. Meurer, a citizen of the United States of America, residing in New York city, in the borough of Manhattan, county and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The instant design consists of a series of darkly colored vertical threads and curly white

horizontal threads, the latter forming interrupted diagonals in opposite directions, the ends of some of such diagonals meeting and forming chevrons and the ends of others of such diagonals terminating within such chevrons, said arrangement of the white horizontal threads creating a similar design in the dark vertical threads, and the whole interspersed with nibs of contrasting yarns, all as shown.

I claim:

The ornamental design for a textile fabric, substantially as shown and described.

LOUIS G. MEURER.
